UNITED STATES PATENT OFFICE.

FRANZ THOMAS, OF SCHMÖLLN, GERMANY.

PROCESS FOR FORMING CASEIN MASSES.

1,159,879.

Specification of Letters Patent.

Patented Nov. 9, 1915.

Application filed December 17, 1912. Serial No. 737,275.

To all whom it may concern:

Be it known that I, FRANZ THOMAS, chemist, subject of the German Emperor, residing at 5 Amtsplatz, Schmölln, Duchy of Saxe-Altenburg, German Empire, have invented a new and useful Improvement in Processes for Forming Casein Masses; and I do hereby declare the following to be a full, clear, and exact description of the same.

This invention relates to a process of and apparatus for forming casein masses, that is to say for producing from a supply of the liquids that are to be dealt with, such as solutions or suspensions of alkali caseinates, solid pieces or articles of the requisite size.

The production of shaped articles made from casein masses by pouring can be effected by pouring solutions or suspensions of alkali caseinates on to the surface of a solution of formaldehyde and a salt which reacts with alkali caseinates (an alkaline earth salt, such as calcium chlorid, magnesium chlorid). By this means more or less spherical articles are obtained. In carrying out this method, it has been found that great care is required in dropping the alkali caseinate into the precipitating liquid, for instance calcium chlorid, and that the article first formed must be removed quickly to avoid the risk of the masses coalescing. This difficulty is especially experienced in making round articles.

The present invention has for its object to obviate the drawbacks above mentioned and in particular to insure reliability in the production of articles in large quantities.

The process consists in distributing the precipitating liquid among a number of compartments which approximately correspond to the dimensions of the globular or other round articles to be produced. A corresponding quantity of the alkali caseinate is allowed to enter each compartment.

An apparatus for carrying out the present method is illustrated in the accompanying drawing. It consists of a grating or series of chambers or cells carried by a plate, which is immersed in the precipitating liquid. The alkali-caseinate solution is then allowed to fall by drops into each separate chamber or cell. There are thus formed

more or less spherical bodies which are separated from one another by the sides or walls of the chambers or cells and are thereby prevented from coalescing. The spheres float on the surface and afterward sink.

Figure 1 is a plan of the grating: and Fig. 2 a side elevation of the said exemplary apparatus.

In the form shown, circular cylinders *b* are arranged on a base plate *a* and are provided at or near the bottom with an opening *c*. After the produced spheres have become hardened the plate *a* can be lifted out of the precipitation vessel, the liquid running away at *c*. Any further treatment required can then be carried on. Of course the sieve-like arrangement can be employed with compartments of any other desired form.

Rough blanks for buttons, beads, and other articles of uniform size and shape can be made in the manner described above.

I claim:

1. The process for making spherical casein masses which consists in arranging within a suitable coagulating liquid a series of separate cells or chambers open at their upper ends and dropping into the coagulating liquid contained in the said cells or chambers freely and separately individual streams of dissolved alkali caseinate in the amounts required to coagulate in the form of individual spherical masses.

2. The process for making spherical casein masses which consists in arranging within a suitable coagulating liquid a series of separate cells or chambers, open at their upper ends, dropping freely and separately into the coagulating liquid contained in each separate cell or chamber individual streams of dissolved alkali caseinate in the amounts required to coagulate in the form of the individual spherical masses and after separating the remaining liquid from the formed individual spherical masses lying in the coagulating liquid.

In testimony whereof I affix my signature in presence of two witnesses.

FRANZ THOMAS.
